UNITED STATES PATENT OFFICE

148,407

DESIGN FOR A CLOTHES HANGER

Walter J. Cleary, Philadelphia, Pa.

Application August 23, 1946, Serial No. 132,768

Term of patent 14 years

(Cl. D80—8)

To all whom it may concern:

Be it known that I, Walter J. Cleary, a citizen of the United States, residing at Philadelphia, in the county of Philadelphia and Commonwealth of Pennsylvania, have invented a new, original, and ornamental Design for Clothes Hanger, of which the following is a specification, reference being had to the accompanying drawing, forming part thereof.

I claim:

The ornamental design for a clothes hanger, as shown.

WALTER J. CLEARY.
